UNITED STATES PATENT OFFICE.

JOHN H. FONES, OF OAKLAND, CALIFORNIA.

WRENCH.

1,302,027.

Specification of Letters Patent. Patented Apr. 29, 1919.

Application filed July 9, 1918. Serial No. 244,048.

To all whom it may concern:

Be it known that I, JOHN H. FONES, a citizen of the United States, residing at Oakland, in the county of Alameda and State of California, have invented new and useful Improvements in Wrenches, of which the following is a specification.

The present invention relates to improvements in wrenches, and the object of the invention is to provide a wrench which can be easily and quickly adjusted to fit any size of nut or bolt and which, when adjusted, can be clamped around the nut or bolt and at the same time be securely locked in its clamping position against accidental release therefrom.

I have herein shown my improvement as applied to a nut wrench, but it is evident that it can, with obvious changes in form, be also applied to a pipe wrench.

In the accompanying drawing, Figure 1 is a side view of my improved nut wrench; Fig. 2 is a longitudinal sectional view on the line 2—2 of Figs. 1, 3; Fig. 3 is a transverse sectional view on the line 3—3 of Fig. 1; Fig. 4 is a broken side view of a modified form of wrench; Fig. 5 is a view similar to Fig. 3 of said modified form.

Referring to the drawing, 1 indicates a jaw, which I shall hereinafter term the stationary jaw, of the wrench, formed integral with a stem or handle 2. Upon said stem can slide a jaw carrier 3 carrying a jaw 4, said jaws 1, 4, having faces 5 extending transversely of the stem so as to be capable of engaging opposite sides of a nut. The jaw carrier 3 is formed with a longitudinally extending and substantially rectangular aperture 10 in which can slide the stem 2, and at the side of said aperture remote from the jaw 4 are two holes 6 in the carrier in which are received pins 7 screwed into one face 8 of a prismatic bar or retainer 9. The other faces 11 of said retainer are formed with ribs or corrugations 12 extending in planes transverse to the bar, and the portion of the prismatic bar remote from the pins 7 is received within a V-shaped groove 13 extending longitudinally in a side 50 of the stem 2 remote from the jaw 1, the

faces of said groove being formed with ribs or corrugations 14 extending in planes transverse to the general direction of the stem and engaging the ribs or corrugations 12 in the faces 11 of the bar to prevent longitudinal movement of said bar in said groove when it is pressed firmly thereinto.

In applying the wrench to a nut, the carrier is slid on the stem until the faces 5 of the jaws 1, 4, engage opposite sides of the nut, and then the carrier is caused to still further advance upon the stem and be at the same time locked in a position by turning a screw 16 contained in a recessed portion of the carrier and rotatable about a shaft 17 threaded at its forward end, as shown at 18, extending through a hole in a portion 19 of said carrier to the rear of said screw, then eccentrically through said screw, and then screwed into a rear portion of the 70 jaw 4.

The threads of the screw 16 engage threads of a rack 15 formed on the side of the stem opposite to that containing the grooves 13, said threads extending across 75 said side obliquely at an angle corresponding to the pitch of the screw 16, so that, if said screw is turned in the proper direction about the shaft 17, the engagement of the screw with the threads of the rack causes 80 the jaw to advance slightly, namely, about one-half of the distance between successive threads. The diameter of the screw 16 and the positions of the shaft 17 relatively to the stem 2 and screw 16 are such that, when 85 the screw is turned so that the portion of its periphery nearest to the shaft 17 lies between said shaft and the stem 2, the carrier can slide freely upon the stem, and therefore the screw must be in such a position to 90 permit the rapid adjustment of the jaw 4 on the stem to properly engage the nut. When this adjustment has been made, however, and the screw is turned not more than one-half of a turn, a portion of the periphery of the screw at, or near that at, the greatest distance from the shaft, engages 95 the threads of the rack. This operation moves the shaft away from the rack, and thereby presses the corrugated faces of the 100

bar 9 into engagement with the corrugated faces of the groove 13, and thus prevents slipping of the carrier upon the stem. It is important that the screw be resiliently held 5 in a central position between the ends of the recessed portion of the carrier. For this purpose there are formed in the faces of the carrier adjacent to the ends of the screw, sockets 20 in which are received short strong 10 coiled springs 21, the outer ends of which press against the ends of said screw. The following is the reason for the provision of springs at opposite ends of the screw, which resiliently hold the screw in a central position 15 in the recessed portion of the carrier. When the threads of the screw engage the teeth of the rack 15, and the screw is turned on its axis, the screw by reason of its inherent property, must move longitudinally 20 through a slight distance as well as rotatably. But it is necessary that it should be capable of rotating, in order to produce a proper engagement of the ribs 12 with the ribs 14. But this engagement of the ribs 25 12 with the ribs 14 prevents the carrier 3 from moving longitudinally upon the stem 2.

Since the carrier 3 is held from longitudinal movement, while it is necessary that the 30 screw 16 should have a longitudinal movement at the same time, it follows that the screw 16 must be normally held in a central position within the recess of the jaw 3 and must be capable of moving to either end of 35 said recess according to the direction to which the screw 16 is turned. While this longitudinal movement of the screw 16 is but small, it is necessary that there should be this longitudinal movement. It is therefore necessary to provide springs at the ends 40 of the screw 16, which normally hold it in a central position in the recess in the jaw 3. It will readily be seen that one spring would render the device occasionally inoperative, 45 for it would press the screw 16 against the other end of said recess, and then, if it were attempted to turn the screw 16 in the direction which, on account of the engagement of the threads of said screw with the rack 15, 50 would cause the screw 16 to advance to the end toward which it was already pressed by the spring, this could not be done, because it is already in contact with said end, and the carrier 3 is prevented from moving longitudinally in the direction which would permit of the desired longitudinal movement of the screw 16 by reason of the engagement of 55 the ribs 12 with the ribs 14.

Evidently the jaw 4 is removed from its 60 clamping position as easily as it is moved thereto, this being done by giving the screw a half-turn so as to remove the shaft toward the rack and then sliding the carrier upon the stem.

In the form of the invention shown in 65 Figs. 4, 5, the stem of the wrench is formed on each side with an undercut portion 22 having transversely extending notches or corrugation 23, and the carrier is formed on each side with an undercut portion 24 70 having notches or corrugations 26 engaging the corrugations 23. The operation of this form of the invention is precisely the same as that first described.

The bar 9, which, on account of the pin 7 75 being received in the hole 6 of the carrier is longitudinally stationary relative to the carrier, may be considered as a removable portion of the carrier.

I claim:—

1. A wrench having a stem having a longitudinally extending rack, a stationary jaw on said stem, a carrier movable on said stem, a jaw carried by said carrier, a longitudinally extending shaft carried by said carrier, a screw eccentrically rotatable on said shaft and adapted in one position on said shaft to engage said rack and in another position being free from said rack, and means for yieldingly maintaining said screw 90 in a central position lengthwise of said shaft, said means functionally opposing the turning movement of said screw.

2. A wrench having a stem and a stationary jaw thereon, said stem having a longitudinally extending rack, a carrier, and a jaw carried thereby, a longitudinally extending shaft carried by said carrier, and a screw eccentrically rotatable on said shaft and adapted in one position on said shaft 100 to engage said rack and in another position being free from said rack, and frictional means for preventing the turning of the screw on its shaft, comprising coiled springs at opposite ends of the screw, of each of 105 which one end is contained in a socket in the carrier, and the other end engages said screw.

3. A wrench having a stem and a stationary jaw thereon, said stem having a longitudinally extending rack, a carrier, and a jaw carried thereby, a longitudinally extending shaft carried by said carrier, and a screw eccentrically rotatable on said shaft and adapted in one position on said shaft to 110 engage said rack and in another position being free from said rack and frictional means for preventing the turning of the screw on its shaft, comprising pairs of coiled springs at opposite ends of the screw, one end of 115 each spring being contained in a socket in a portion of the carrier adjacent to the adjacent end of said screw, and the other end engaging said screw end.

4. A wrench having a stem and a stationary jaw thereon, said stem having a longitudinally extending rack, a carrier and a jaw carried thereby, a longitudinally ex-

tending shaft carried by said carrier, a screw eccentrically rotatable on said shaft and adapted in one position on said shaft to engage said rack and in another position being free from said rack, said carrier having a removable portion longitudinally stationary in regard to the carrier, said stem and removable portion of the carrier having cor-

rugations adapted to engage each other and prevent longitudinal movement of the carrier on the stem when the screw is turned on its shaft, the carrier having holes, and the removable portion having pins removably contained in said holes. 10
